UNITED STATES PATENT OFFICE.

ERNEST G. BRIGGS, OF BROOKVILLE, PENNSYLVANIA.

AEROPLANE.

1,264,152.

Specification of Letters Patent.

Patented Apr. 30, 1918.

Application filed August 1, 1916. Serial No. 112,586.

To all whom it may concern:

Be it known that I, ERNEST G. BRIGGS, a citizen of the United States, residing at Brookville, in the county of Jefferson and 5 State of Pennsylvania, have invented certain new and useful Improvements in Aeroplanes, of which the following is a specification.

This invention relates to aeroplanes, and 10 more particularly to means for stabilizing aeroplanes and for preventing too rapid descent of the same in case of accident.

One of the main objects of the invention is to provide an aeroplane of simple construction and operation which will remain steady in swirls or high winds. A further object is to provide an aeroplane with means for exerting a parachute effect in case of accident to the motor, so as to prevent a too 20 rapid descent of the plane.

In the drawings:—

Figure 1 is a plan view of the invention.

Fig. 2 is a side view partly broken away with the main plane omitted, and

25 Fig. 3 is a front view partly in section.

1 designates the boat or body of the plane in the forward part of which is mounted the engine 2 of suitable construction. The propeller 3 projects forward of the body 30 and is operatively connected to the engine so as to be rotated thereby.

The main plane 4 is mounted near the front of boat 1 and extends a considerable distance from each side of the same. This 35 plane is of usual construction and carries, at each side of boat 1, a base 5. A vertical shaft 6 is rotatably mounted in each of the bases 5 and is braced by suitable collars 7 mounted about the same and supported by 40 stay rods 8 secured to the plane 4 and the sides of body 1. A circular plane 9 is firmly secured on the upper end of each shaft 6 so as to be rotated thereby.

A horizontal steering plane 10 is mounted. 45 at the back of boat 1 and is adapted to be tilted so as to vary the angle of the machine so as to ascend or descend, as desired, in the usual manner. In back of plane 10 the vertical rudder 11 is mounted for movement 50 laterally so as to steer the machine to either side in the manner now well known in this art.

The body 1 is mounted on light pneumatic wheels 12 and 13 so as to support it 55 for raising the machine from the ground by running forward until sufficient speed has

been attained to lift the machine off the ground in the usual manner.

A beveled gear 14 is keyed to each shaft 6, near the lower end thereof. This gear 60 meshes with a similar gear 15 keyed on the outer end of a shaft 16 rotatable in standards 17. A beveled gear 18 is keyed on the inner end of shaft 16 and meshes with a beveled driving gear 19 keyed on the engine 65 shaft 20.

When the shaft 20 is rotated the planes 9 are revolved at a comparatively high speed in opposite directions. As these planes are rotating they have a constant tendency to 70 remain in a horizontal plane and resist any force tending to move them out of this plane. As they rotate in opposite directions, any force which tends to move one of them out of the horizontal would not only be resisted by the plane upon which this force is directly exerted, but would also be equally resisted by the other plane. These two planes really constitute, so far as their stabilizing effect is concerned, two oppositely 75 revolving gyroscopes, and act in the same manner in resisting forces which tend to move them out of a horizontal plane, and to overcome such forces and return to a horizontal plane if they be moved out of it. 80

In addition to acting as stabilizing elements, the planes 9 are of material assistance in steadyng the plane in high winds or swirls. Due to the fact that they rotate outwardly and forwardly from the body 1 90 they act to turn unusually large bodies of air to each side of the machine, thus opening a path for the machine which in this manner escapes the direct effect of the air body encountered. As the amount of air which 95 is thus turned aside by one plane will be equal to the amount which is turned aside by the other plane, the machine will be maintained on an even keel. If the engine becomes disabled, the planes 9 will exert a 100 strong parachute effect so as to prevent a too rapid descent.

When the planes 9 are disconnected from the engine, by a suitable clutch mechanism of standard construction (not shown) provided for this purpose, they will remain stationary. Under these conditions the planes 9 will coöperate with the main plane 4 to raise the machine and sustain it in the air. For this purpose the planes 9 have their 110 peripheral edges formed very thin so as to readily cut through the air and thus reduce

the resistance to the forward travel of the machine to a minimum.

I have shown the planes 9 as revoluble by the same engine as is used for rotating the propeller 3, but I desire it to be understood that I do not limit myself to this particular form of drive. These planes may be operated in numerous other ways, as by an independent motor, or may even be adapted 10 to be driven either by an independent motor or by the propeller motor, optionally. My invention resides more particularly in the provision of supplemental planes in spaced relation to the main plane and adapted to 15 be optionally revolved, and not in the particular means for revolving these planes.

Although I have shown the planes 9 as located above the main plane 4, very good results may be obtained by placing them below the main plane. Also, the two planes 9 20 may be replaced by a single revoluble plane positioned at the center of the main plane without departing from the principle of my invention.

25 While I have shown the planes 9 as being perfectly flat, it will be evident that they can be made in numerous shapes, either concave or convex, or other shape, as may be deemed expedient. There may also be numerous changes made in the other parts of 30

my invention without departing from the field and scope of the same, and I intend to include all such variations in this application, in which the preferred form only of my invention is disclosed. 35

What I claim is:

In an aeroplane, a body, a main plane projecting from each side of and beneath the body, supporting bases secured on the upper surface of said plane at each side of, and 40 equi-distant from, the body, vertical shafts rotatably supported by said bases, flat circular planes secured on the upper ends of said shafts, a motor carried by the body, and driving connections between said motor 45 and shafts for causing simultaneous rotation of the shafts in opposite direction whereby the planes mounted at the upper ends of said shafts will be rotated oppositely simultaneously and in a plane 50 above the said main plane so as to resist forces tending to cause rocking of the aeroplane about the longitudinal axis of said body.

In testimony whereof I affix my signature 55 in presence of a witness.

ERNEST G. BRIGGS.
